(57) **CLAIM**

The ornamental design for an automotive instrumentation receiver, as shown and described.

DESCRIPTION

FIG. 1 is an isometric view of an automotive instrumentation receiver showing my new design.

FIG. 2 is a front plan view thereof.

FIG. 3 is a right side plan view thereof.

FIG. 4 is a left side plan view thereof.

FIG. 5 is a top plan view thereof.

FIG. 6 is a rear plan view thereof.

FIG. 7 is a bottom plan view of the automotive instrumentation receiver shown with the lid removed; and,

FIG. 8 is an exploded isometric view thereof.

The broken line showing of environment is for illustrative purposes only and forms no part of the claimed design.
